(57) **CLAIM**

The ornamental design for a compact portable animal washer, as shown and described.

DESCRIPTION

FIG. 1 is a right perspective view of a compact portable animal washer.

FIG. 2 is a left side elevation view thereof;

FIG. 3 is a front view thereof;

FIG. 4 is a right side elevation view thereof;

FIG. 5 is a rear view thereof;

FIG. 6 is a top plan view thereof; and,

FIG. 7 is a bottom plan view thereof.

The broken lines in the drawings are for illustrative purposes only and form no part of the claimed design.
